UNITED STATES PATENT OFFICE

WILLIAM ROBERT CLUFF, OF NEW YORK, N. Y.

DESIGN FOR A TABLE COVER

Application filed December 28, 1929. Serial No. 33,970. Term of patent 3½ years.

To all whom it may concern:

Be it known that I, WILLIAM ROBERT CLUFF, a citizen of the United States, residing at New York, in the county of New York and State of New York, have invented a new, original, and ornamental Design for a Table Cover, of which the following is a specification, reference being had to the accompanying drawing, forming part thereof.

The figure is a face view of a table cover, showing my new design.

I claim:

The ornamental design for a table cover, as shown.

In testimony whereof I have affixed my signature.

WILLIAM ROBERT CLUFF.
